APPARATUS FOR THE DRAFTING OF
TEXTILE FIBERSGeoffrey Hill Ambler, Hikley, England, assignor
to Ambler Superdraft Limited, Yorkshire, Eng-
land, a British company

Application March 5, 1951, Serial No. 213,935

Claims priority, application Great Britain
March 25, 1950

10 Claims. (Cl. 19—130)

1

This invention relates to drafting apparatus for the drafting of textile fibres by the method of drafting described in U. S. application Serial No. 151,136, on which Patent No. 2,641,026 was granted June 9, 1953, said application having been a continuation-in-part of applicant's application Serial No. 18,524, filed April 2, 1948, now abandoned in favor of the application for said patent. Whilst this specification is particularly concerned with the drafting of rovings in the final spinning operation, the same principles of drafting can be applied to the earlier stages of drafting in the preparation of slubbings and the final roving from which yarn is spun, and it is with such apparatus for performing such earlier stages of drafting that the present invention is concerned. An object of the invention is to provide a compact intermediate unit consisting of certain parts of the apparatus and capable of ready attachment to the main drafting apparatus.

In the preparation of slubbings, rovings and the like, it is usual to carry out a series of doublings, i. e. feeding two or more slubbings or the like together to the same pair of drafting rollers so as to produce a single slubbing. For the sake of clarity in this specification, the material fed to the apparatus will be referred to as a "slubbing" and the material produced from the slubbing by the apparatus according to the invention will be referred to as a "roving."

According to the present invention, there is provided an intermediate unit comprising a main body adapted for attachment to a drafting apparatus between feed and drafting rollers, a series of lower intermediate rollers attached to a common shaft rotatably mounted in the main body, a series of upper intermediate rollers rotatably mounted in the main body and each adapted to co-operate with a lower roller to receive a slubbing from the feed rollers and urge it towards drafting rollers, and gearing for connecting at least the common shaft to driving gear in the drafting apparatus. Preferably, the upper rollers are also positively driven, either directly from driving gear in the drafting apparatus or by intermediate gearing mounted in the unit and connecting the upper rollers to the common shaft of the lower rollers.

The upper rollers are preferably individually mounted in supporting brackets pivotally mounted on the unit and arranged to swing upwardly for threading purposes, the brackets carrying weights (or being themselves of sufficient weight) for supplying the necessary pressure at the nips of the intermediate rollers. In such a case, the upper rollers may be driven by driving gears secured to a common intermediate shaft itself

2

driven through intermediate gearing from the common lower roller shaft (or from the driving gear in the drafting apparatus), the supporting brackets conveniently being pivotally mounted on the common intermediate shaft and each carrying intermediate gearing connecting the upper roller to its driving gear.

Preferably, one intermediate roller of each pair, e. g. the lower one, is provided with a pair of flanges between which the other roller runs and rests on the slubbing passing between them, the flanges being spaced apart a distance somewhat less than the free diameter of the slubbing, the weights then causing the slubbing to be compressed between the rollers and the flanges into a compact section that will allow the initial twist in the slubbing continuously to pass through the nip of the intermediate rollers. Guides are preferably arranged on the main body for leading the individual slubbings into the nips of the respective intermediate rollers.

A series of channel-shaped members or "flumes" (one for each pair of rollers) may be mounted on the main body forwardly of the intermediate rollers for the purpose described in the specification mentioned above, and a series of similar members may be mounted on the main body behind the intermediate rollers.

By way of example, a drafting apparatus 30 equipped with intermediate units according to the invention will now be described in greater detail with reference to the accompanying drawings, in which

Figure 1 is a diagram in elevation of the salient features of the drafting apparatus, showing a unit in operative position.

Figure 2 is a diagrammatic plan of the apparatus shown in Figure 1;

Figure 3 is an elevation of one side of a unit 40 with part of the front structure removed;

Figure 4 is a front end view of the unit shown in Figure 3;

Figure 5 is a cross-section of the unit taken along the line 5—5 in Figure 3;

Figure 6 is an elevation of the side of the unit opposite to that shown in Figure 3, with part of the structure broken away;

Figure 7 is a cross-section of the unit taken along the line 7—7 in Figure 5;

Figure 8 is a cross-section of the unit taken along the line 8—8 in Figure 5;

Figure 9 is a plan of the unit partly in section and having parts of the upper structure omitted, and

Figure 10 is a diagram showing the gearing for driving the intermediate rollers.

Referring first to Figures 1 and 2, a series of

four slubbings 11 are each passed from feed rollers 12 to the nip of a pair of intermediate rollers 13 and 14, and from there through a flume 16 to the nip of drafting rollers 17 and 18, the four drafted slubbings 11 being collected from the drafting rollers 17 and 18 and twisted together to form a single roving 19 by a flyer device (not shown) of known construction.

The intermediate rollers 13 and 14, flumes 16 and gearing for driving the intermediate rollers are all mounted in a self-contained unit according to the invention (indicated generally in Figures 1 and 2 by reference numeral 21) which, as will be seen from later description, is readily detachable as a whole from the drafting apparatus for cleaning, repair or replacement purposes.

The unit 21 is supported in the drafting apparatus by means of a semi-circular bearing surface 22 formed on the lower surface of the main body 23 of the unit and arranged to rest on the upper surface of a bearing member 24 forming part of the drafting apparatus, the bearing member 24 being secured to a support 26 extending lengthwise of the apparatus.

Referring to Figures 3 to 10, the lower rollers 14 are each formed with a pair of flanges 27 (see Figures 5 and 8) between which an upper roller 13 fits closely and rests on the slubbing 11 passing between the flanges. The rollers 14 are secured to a common shaft 28 rotatably mounted in bearings in the main body 23. Gears 29 and 31 are secured to opposite ends of the shaft 28. The gear 29 drives, through intermediate gears 32, 33 and 34 freely mounted in the main body 23, a gear 36 secured to an intermediate shaft 37 rotatably mounted in bearings in the main body 23. The gear 31 engages an idler gear 38 freely mounted in the body 23. The idler gear 38 (or the intermediate gear 32, as will be explained later) is arranged in engagement with a main driving gear 39 secured to a common driving shaft 41 forming part of the drafting apparatus.

The upper rollers 13 are each rotatably mounted in a separate supporting bracket 42 pivotally mounted on the intermediate shaft 37, the rollers 13 being formed integrally with their supporting shafts to which are secured gears 43. Freely mounted in each bracket 42 are two intermediate gears 44 and 46 connecting the roller gear 43 to a gear 47 secured to the intermediate shaft 37. It will thus be seen that, as any bracket 42 is swung upwardly into "open" position (see Figure 3) for threading or other purposes, the gears 43, 44, 46 and 47 remain in constant mesh, the gear 46 merely rolling around the gear 47. The weight of the brackets 42 and their gearing is sufficient to supply the necessary pressure at the nips of the intermediate rollers, each bracket 42 with its gearing thus constituting an individual weighting means.

Roving guides 48 are provided for leading the individual slubbings 11 to the nips of the intermediate rollers 13 and 14, the guides being formed integrally with a common support 49 attached to the main body 23, each guide 48 being cut away to clear the flanges 27 of its lower roller 14, leaving a tongue 50 projecting between the flanges to carry the base of the guide close to the roller surface.

The flumes 16 are formed with apertures 51 of rectangular cross-section having a narrow gap 52 for threading purposes, the flumes being formed integrally with a common support 53 attached to the main body 23.

The unit 21 is attached to the drafting apparatus by a pair of spring-loaded pins 54 slidably mounted in the body 23 and arranged to engage a corresponding pair of holes in a saddle member 56 forming part of the drafting apparatus. The pins 54 are actuated (to release the unit from the saddle member 56) by inward pressure on a pair of studs 57 extending from the pins 54 through slots 58 in the body 23. The unit is thus readily detachable as a whole from the drafting apparatus.

The saddle member 56 is in the form of a frame embracing an extension 59 of the bearing member 24 in which is slidably mounted a pair of rods 61 and 62, the saddle member 56 being attached to the rods on each side of the extension 59 with the frame having its walls spaced from the extension so as to be movable with the rods relatively to the extension. The saddle member 56 (with its attached unit 21) may thus be traversed bodily in a direction parallel to the drafting roller axes by movement of the rods 61 and 62 in the extension 59.

As applied to a drafting apparatus of normal construction for producing single rovings from a plurality of slubbings, one unit 21 is provided for each spindle on the apparatus. It is found convenient, however, to mount the units in sections each having a common support 26 and a common rod 62 provided with traversing mechanism (not shown). A bearing member 24 is provided for each unit, and the end bearing members in each section serve also as bearings for the common driving shaft 41 to which is secured a series of the gears 39 for driving the units, the common shaft 41 being driven by gearing (not shown) from a suitable driving member on the drafting apparatus. The gears 39 are arranged between the bearing members 24 and each serves to drive two units 21 (by engaging the gears 38 of one unit and the gear 32 of an adjacent unit) as illustrated in Figure 10.

The supports 26 of the various sections are connected to a common adjusting mechanism (not shown) by means of which the units as a whole may be adjusted towards and away from the drafting rollers, as required for different degrees of draft.

What I claim is:

1. An intermediate unit for a drafting apparatus of the kind including feed rollers, drafting rollers and a driving shaft, said intermediate unit comprising a main body adapted for attachment to the drafting apparatus between the feed and drafting rollers, a common shaft rotatably mounted in the main body, a series of lower intermediate rollers attached to said common shaft, a series of upper intermediate rollers each adapted to co-operate with a lower roller to receive a slubbing from the feed rollers and urge it towards the drafting rollers, a series of individual supporting brackets in which the upper intermediate rollers are rotatably mounted, an intermediate shaft, the brackets being pivotally mounted on said intermediate shaft and arranged to swing upwardly for threading purposes, weighting means on each bracket for supplying the necessary pressure individually at the nip of each pair of the intermediate rollers, gears secured to said intermediate shaft for driving the upper intermediate rollers, intermediate gearing carried by each bracket for connecting the upper roller mounted in that bracket to its driving gear and gearing for connecting said

intermediate shaft to the driving shaft in the drafting apparatus.

2. A unit as specified in claim 1 and in which one roller of each pair of intermediate rollers is formed with a pair of flanges between which the other roller of the pair runs and rests on the slubbing passing between them.

3. A unit as specified in claim 2, and in which a series of guides is mounted on the main body and arranged to lead the individual slubbings into the nips of the respective intermediate rollers.

4. A unit as specified in claim 3, and in which a series of flumes is mounted on the main body forwardly of the intermediate rollers, the flumes being arranged in alignment with the respective pairs of rollers.

5. A unit as specified in claim 4, and in which a pair of spring-loaded pins is slidably mounted in the main body for attaching the units to the drafting apparatus.

6. An intermediate unit for a drafting apparatus of the kind including feed rollers, drafting rollers and a driving shaft, said intermediate unit comprising a main body adapted for attachment to the drafting apparatus between the feed and drafting rollers, a common shaft rotatably mounted in the main body, a series of lower intermediate rollers attached to said common shaft, a series of upper intermediate rollers each adapted to co-operate with a lower roller to receive a slubbing from the feed rollers and urge it towards the drafting rollers, a series of individual supporting brackets in which the upper intermediate rollers are rotatably mounted, an intermediate shaft, the brackets being pivotally mounted on said intermediate shaft and arranged to swing upwardly for threading purposes, weighting means on each bracket for supplying the necessary pressure individually at the nip of each pair of the intermediate rollers, gears secured to said intermediate shaft for driving the upper intermediate rollers, intermediate gearing carried by each bracket for connecting the upper roller mounted in that bracket to its driving gear and gearing for connecting at least the common shaft to the driving shaft in the drafting apparatus.

7. A unit as specified in claim 6, and in which one roller of each pair of intermediate rollers is formed with a pair of flanges between which the other roller of the pair runs and rests on the slubbing passing between them.

8. Drafting apparatus comprising feed rollers, drafting rollers, driving gear and an intermediate unit arranged between the feed and drafting rollers for adjustment towards and away from the drafting rollers, said unit comprising a main body attached to the drafting apparatus, a common shaft rotatably mounted in the main body, a series of lower intermediate rollers attached to said common shaft, a series of upper intermediate rollers each adapted to co-operate with a lower roller to receive a slubbing from the feed rollers and urge it towards the drafting rollers, a series of individual supporting brackets, in which the upper intermediate rollers are rotatably mounted, an intermediate shaft, the brackets being pivotally mounted on said intermediate shaft and arranged to swing upwardly for threading purposes, weighting means on each bracket for supplying the necessary pressure individually at the nip of each pair of the intermediate rollers, gears secured to said intermediate shaft for driving the upper intermediate rollers, intermediate gearing carried by each

bracket for connecting the upper roller mounted in that bracket to its driving gear and gearing for connecting at least the common shaft to the driving gear in the drafting apparatus.

9. Drafting apparatus comprising feed rollers, drafting rollers, a driving shaft and an intermediate unit arranged between the feed and drafting rollers for adjustment towards and away from the drafting rollers, said unit comprising a main body attached to the drafting apparatus, a common shaft rotatably mounted in the main body, a series of lower intermediate rollers attached to said common shaft, a series of upper intermediate rollers each adapted to co-operate with a lower roller to receive a slubbing from the feed rollers and urge it towards the drafting rollers, flanges formed on one roller of each pair of upper and lower rollers between which the other roller of the pair fits closely and rests on the slubbing passing between the flanges, a series of individual supporting brackets in which the upper intermediate rollers are rotatably mounted, an intermediate shaft, the brackets being pivotally mounted on said intermediate shaft and arranged to swing upwardly for threading purposes, weighting means on each bracket for supplying the necessary pressure individually at the nip of each pair of the intermediate rollers, gears secured to said intermediate shaft for driving the upper intermediate rollers, intermediate gearing carried by each bracket for connecting the upper roller mounted in that bracket to its driving gear, gearing for connecting the upper and lower rollers to the driving shaft in the drafting apparatus, and a series of flumes mounted on the main body forwardly of the intermediate rollers in alignment with those rollers.

10. A detachable intermediate unit for a drafting apparatus of the kind including feed rollers, drafting rollers and a driving shaft, comprising a main body adapted to be located in the drafting apparatus between feed and drafting rollers, means on said body for detachably mounting it on the drafting apparatus, a common shaft rotatably mounted in the main body, a series of lower intermediate rollers attached in spaced relationship to said common shaft, a series of upper intermediate rollers rotatably mounted in the main body and each adapted to co-operate with a lower roller to receive a slubbing from the feed rollers and urge it towards the drafting rollers, a series of individual supporting brackets in which the upper intermediate rollers are rotatably mounted, an intermediate shaft, the brackets being pivotally mounted on said intermediate shaft and arranged to swing upwardly for threading purposes, weighting means for each of the upper rollers for supplying the necessary pressure individually at the nip of each pair of the rollers, and gearing for connecting at least the common shaft to the driving shaft in the drafting apparatus.
